UNITED STATES PATENT OFFICE.

FRANK GREEN, OF BATESVILLE, INDIANA.

EGG TESTER.

Application filed August 8, 1924. Serial No. 730,874.

To all whom it may concern:

Be it known that FRANK GREEN, a citizen of the United States, residing at Batesville, in the county of Ripley and State of Indiana, has invented certain new and useful Improvements in Egg Testers, of which the following is a specification.

This invention relates to new and useful improvements in egg testers.

10 The primary object of this invention is to greatly expedite the testing of eggs by breeders, dealers and packers by providing a device of this character whereby an entire row of eggs may be tested by the operator at a

15 single glance.

A further object of my invention is to provide a device of this character which is simple and economical in construction and highly efficient and durable in use.

20 With the foregoing and other objects in view that will appear as the nature of my invention is better understood, the same consists in the novel features of construction, combination and arrangement of parts illus-

25 trated in the drawings and more particularly pointed out in the appended claims.

In the accompanying drawings which are for illustrative purposes only and are therefore not drawn to scale:

30 Figure 1 is a side elevation of an egg tester embodying my improvements.

Figure 2 is a plan view.

Figure 3 is a central longitudinal section, taken on line 3—3 of Figure 2.

35 Figure 4 is a vertical transverse section, taken on line 4—4 of Figure 3.

The other views are views of details of construction.

Referring to the drawings for a more particular description of my invention and in which drawings like parts are designated by like reference characters throughout the several views, the device comprises a table consisting of the legs 1, top 2 and the side 40 and end panels 3 and 4, respectively. The top 2 is made in two corresponding sections *a* and *b* which may be adjusted closer together or farther apart to leave a vertical space 5, one-eighth to one-fourth of an 45 inch in width, extending entirely across the table top to suit the convenience and meet the requirements of the operator. This space is to permit the passage of the rays of light from the reflector 6. The reflector 6 is con-

50 structed from a single continuous strip of tin or other suitable reflecting material hav-

ing its side edges 7 and 8 fastened to the oppositely disposed recessed inner ends 9 and 10 of the table top sections *a* and *b*, respectively. Said reflector is bent into such 60 form that it is substantially oval in cross section when the inner ends of the table top sections are spread apart and of perfect cylindrical form when said sections are entirely closed. The reflector extends across 65 the full width of the table top and screwed into the side panels 3 of the latter, as at 11, and extending into the ends of the reflector, are a pair of electric lamps 12 which furnish the necessary illumination.

70 The table top is of the proper width to permit breeders to use incubator trays and to test eggs without removing them from the trays by passing the latter slowly over the vertical space 5 of the top and testing 75 an entire row of eggs at one time. The table top is preferably provided along its side edges with longitudinal upwardly projecting guide flanges 13, the purposes of which are apparent.

80 For dealers and packers, I provide a special tray 14 with a wire screen bottom 15 on which the eggs are placed in transverse rows. To test the eggs this tray is moved over the top and each transverse row of 85 eggs may be tested at a glance as it comes directly over the space 5 through which a strong light is reflected by the electric lamps and reflector heretofore mentioned. The screen or wire bottom 15 of the tray 90 14 is so constructed that the eggs will naturally roll into transverse rows as closely as possible when the eggs are casually placed in the tray.

95 In the modified form of my invention illustrated in Figure 5 of the drawings, the egg tray is provided with a solid wooden or metal bottom 15' formed with transverse rows of openings 16 in which the eggs are supported. In the modified form of my invention illustrated in Figure 6, the reflector is provided along its bottom with a series 100 of longitudinally spaced electric lamps 12' to furnish the required illumination, instead of employing electric lamps at the 105 ends of the reflector.

From the foregoing description taken in connection with the drawings, it is thought that the construction, operation and advantages of my invention will be readily understood without requiring a more extended explanation.

Various changes in the form, proportions and minor details of construction may be resorted to without departing from the principle or sacrificing any of the advantages of this invention as defined in the appended claims.

Having described my invention what I claim as new and desire to secure by Letters Patent, is:—

10. 1. In a device of the character specified, a table comprising a top composed of two corresponding longitudinally adjustable sections, a reflector constructed from a single strip of metal having its edges secured to the inner edges of the table top sections and a plurality of electric lamps arranged in said reflector.
20. 2. In a device of the character specified, a table comprising a top composed of two corresponding longitudinally adjustable sections, a reflector constructed from a single strip of metal having its edges secured to the inner edges of the table top sections and a plurality of electric lamps arranged in said reflector, said reflector being of perfect cylindrical form when the table top sections are together and of substantially oval form when moved slightly apart.
25. 3. In a device of the character specified,

30 a table top comprising two corresponding longitudinally adjustable sections and side and end panels, a reflector constructed from a single strip of reflecting material arranged with its edges secured to the inner ends of the table top sections, said reflector being 35 of perfect cylindrical form when said sections are entirely closed and substantially oval in cross section when slightly separated, lamps screwed to the side panels of the top and extending into the ends of the reflector 40 and a tray movable over the table top.

4. In a device of the character specified, a table top comprising two corresponding longitudinally adjustable sections and side and end panels, a reflector constructed from 45 a single strip of reflecting material arranged with its edges secured to the inner ends of the table top sections, said reflector being of perfect cylindrical form when said sections are entirely closed and substantially oval in cross section when slightly separated, lamps screwed to the side panels of the top and extending into the ends of the reflector 50 and a tray with a wire screen bottom movable longitudinally over the table top. 55

In testimony whereof I affix my signature.

FRANK GREEN.
